UNITED STATES PATENT OFFICE.

TON V. K. HOTT, OF DAYTON, OHIO, ASSIGNOR TO THE JOYCE-CRIDLAND COMPANY, OF DAYTON, OHIO, A CORPORATION OF OHIO.

LIFTING JACK.

Application filed January 21, 1925. Serial No. 3,741.

This invention relates to lifting jacks and more particularly to that type of lifting jack in which the downward movement of the lifting element under the weight of the 5 load is regulated by suitable retarding devices under the control of the operator.

One object of the invention is to provide a controlling device for a jack of this kind which will be simple in its construction, 10 positive in its operation, and having means for easily controlling the same.

A further object of the invention is to provide such a mechanism in which the retarding device will be rendered operative by the 15 end thrust on a worm and having means for rendering the retarding device inoperative and rotating the worm.

A further object of the invention is to provide an improved operating device for 20 controlling the action of the retarding device for rotating the worm.

Other objects of the invention will appear as the device is described in detail.

In the accompanying drawings Fig. 1 is 25 a front elevation of a jack embodying my invention; Fig. 2 is a similar view with the controlling mechanism partly in section; Fig. 3 is a section view of the controlling mechanism taken on the line 3-3 of Fig. 2; Fig. 4 is a plan view of the housing for 30 the controlling mechanism showing the handle in section, on the line 4-4 of Fig. 5; Fig. 5 is a longitudinal section of the controlling mechanism showing the brake in its 35 operative position; Fig. 6 is a similar view showing the brake in an inoperative position; Fig. 7 is an end elevation of the controlling mechanism showing the handle in its operative position; Fig. 8 is a similar 40 view showing the handle advanced to release the brake; and Fig. 9 is a perspective detail view of the handle and its connecting devices, partly broken away.

In these drawings I have illustrated one 45 embodiment of my invention and have shown the same as applied to a lifting jack of a well known type but it will be understood that the mechanism may take various forms and may be applied to jacks of various kinds without departing from the spirit 50 of the invention.

As here shown, the jack comprises a base 1 on which is mounted an upwardly extending housing or hollow standard 2 within 55 which is provided a bearing for a lifting

element or ram 3 which is also hollow and is provided at its lower end with a nut 4 to receive a screw 5 which is rotatably mounted at its lower end on the base 1, all in a well known manner. Rigidly secured to the 60 shank of the screw 5 near the base 1 is a beveled gear 6 which meshes with a beveled pinion 7 rigidly secured to or formed integral with a shaft 8 which is journaled in bearings 9 and 10 in the housing or standard 65 2 and in a third bearing 11 formed in a supplemental housing 12 which is secured to the side of the main housing or standard and which encloses the controlling mechanism. The beveled pinion is connected with 70 a suitable operating device by means of which it may be rotated to rotate the screw 5 and elevate the lifting element. In the present jack reducing gearing is interposed between the operating device and the beveled 75 pinion and to this end I have mounted on the shaft 8, within the housing 12, a gear 13 which meshes with a second gear 14 secured to a shaft 15 mounted in bearings 16 and 17. The outer end of the shaft projects beyond the outer wall of the housing 12 to receive the operating device. As here shown, the operating device is in the form 80 of a lever socket 18 adapted to receive an operating lever and connected with the shaft 15 by the usual pawl and ratchet mechanism. The operating device forms no part of the 85 present invention and it is not necessary that it be shown in detail.

The screw 5 is of the high pitch type and 90 will rotate under the weight of a load, when unrestrained. In order to control the rotation of the screw under the weight of the load I have secured to the shaft 15 a worm 95 wheel 19 which meshes with a worm 20 mounted on the shaft 21 extending transversely to the shaft 15 and journaled in bearings 22 and 23 formed in the housing 12. The shaft 21 is capable of a slight longitudinal movement, as well as a rotatory 100 movement, and rigidly secured thereto is a brake member 24, here shown as a tapered friction member adapted to enter a tapered seat 25 which constitutes the cooperating friction member and is, in the present instance, formed integral with the housing 12. The brake member 24 may be secured to the 105 shaft in any suitable manner but, as here shown, the outer end of this member is recessed, as shown at 26, to receive a collar 27 110

rigidly secured to and preferably formed integral with the shaft. This collar is connected with the brake member by means of keys 28 so that the brake member will be caused to rotate with the shaft and to move longitudinally therewith. The worm 20 is loosely mounted on the shaft 21 so that it may have rotatory and axial movement with relation thereto. When the worm wheel 19 is rotated by the screw 5 upon the downward movement of the load it will impart to the worm 20 an end thrust toward the brake member 24 and this thrust will force the brake member into firm frictional contact with the cooperating friction surface 25 and thereby hold the worm wheel and screw against further movement. This holding device is constantly operative and will instantly check the reverse movement of the load between the successive operations of the operating lever on the shaft 15. When the worm 19 is rotated in a forward direction by the rotation of the shaft 15, by means of the operating lever, the end thrust imparted to the worm 20 will move the worm in the opposite direction and will release the same for rotation with the worm wheel. In the present instance, the worm is formed separate from the brake member 24 and the adjacent ends of the worm and brake member are provided with cooperating clutch teeth 29. The end thrust imparted to the worm by the forward movement of the worm wheel 19 will disengage these clutch teeth to permit the worm to rotate relatively to the shaft 21 and the brake member. To reduce to a minimum the frictional resistance to the rotation of the worm I have interposed between the end thereof and the bearing 23 an anti-friction end thrust bearing 30 with which the end of the worm will contact when it is moved to the right, in Fig. 2, by the forward movement of the worm wheel 19. It will be apparent, therefore, that when the lifting mechanism is operated to elevate the load the worm 20 will rotate freely with the worm wheel 19 and will offer no appreciable resistance to the operation of the mechanism, but as soon as the operation of the lifting mechanism is interrupted the weight of the load will impart a reverse movement to the worm wheel 19 which will cause the worm to be instantly connected with the brake member 24 and this brake member firmly seated against its cooperating brake member, thus instantly locking the worm against rotation and thereby locking the load against downward movement.

When it is desired to lower the load the brake member 24 is moved to an inoperative position but its connection with the worm 20 is maintained so that this worm cannot be rotated with relation to the shaft 21 by the reverse movement of the worm wheel 19. This is accomplished by imparting axial

movement to the shaft 21 and to this end I have mounted on that shaft a sleeve or hub member 31 which bears against the end of the bearing 23 and which is provided with a helical slot 32 through which extends a pin 33 rigidly mounted in the shaft 21 and retained therein by a screw 34. The arrangement of the slot 32 is such that when the sleeve is rotated in a direction to lower the load the inclined wall of the slot will act on the pin 33 to impart axial movement to the shaft 21 and thereby move the brake member 24 into an inoperative position. Movement is imparted to the sleeve 31 by means of a crank or handle 35 which is mounted thereon and as here shown this handle is mounted on a pin or shaft 36 mounted in lugs 37 formed integral with the sleeve 31 so that it may be moved into an inoperative position, as shown in Fig. 2, when not in use. In order to retain the handle in either its operative or its inoperative position the hub portion 38 thereof is provided with two recesses 39 spaced apart and adapted to receive a detent. In the present device, this detent is in the form of a plunger 40 slidably mounted in lugs 37 parallel with the axis of the handle and having an enlarged portion 41 which may be moved into and out of the recesses 39. That end of the plunger opposite the enlarged portion 41 thereof extends through a hollow boss 42 forming a part of one of the lugs 37 and has mounted thereon a head 43 between which and the lug is coiled a spring 44 which tends to move the enlarged end of the plunger into its operative position. The pressure of the thumb upon the head 43 will move the plunger against the tension of the spring 44 and disengage the detent portion thereof from the hub of the handle. The recesses 39 in the hub of the handle are so arranged that one of them will be in line with the detent when the handle is in its operative position and the other will be in line with the detent when the handle is in its inoperative position. To insure the release of the shaft and brake member from the sleeve 31 the hub of the handle is provided with an inclined or cam surface 45 which is arranged to engage the pin 33 when the handle is moved to its inoperative position and to thus shift the pin to the inner end of the helical slot 32. When the handle 35 is in its folded or inoperative position, as shown in Fig. 2, it lies back of a lug 46 on the frame or bearing in which the shaft 21 is journaled and thereby locks the shaft against movement in a lowering direction and positively prevents the lowering of the load until the handle has been moved into an operative position.

The operation of the device will be readily understood from the foregoing description and it will be apparent that when the lift-

ing mechanism is operated to elevate the load the worm wheel 19 will rotate in a forward direction and that the thrust imparted to the worm 20 by this worm wheel 5 will disengage the worm from the brake member and release the same for free rotation on the shaft 21. When the pressure on the operating device for the lifting mechanism is released the load on the lifting element will rotate the screw 5 in a reverse direction and thereby impart reverse movement to the worm wheel 19. This reverse movement of the worm wheel 19 will impart axial movement to the worm 20 which will cause it to engage the brake member 24 and to force that member firmly against its cooperating friction surface and when thus seated the brake and worm will hold the worm wheel and screw against 20 reverse movement. When the load is to be lowered the handle 35 is moved into its operative position and forward movement imparted thereto, that is, the movement which will tend to rotate the shaft and worm 20 in a direction to permit the load to move downwardly. This forward movement of the handle and the sleeve 31 with which it is connected causes the inclined wall of the slot 32 to act on the pin 33 and 30 impart axial movement to the shaft 21, thus moving the brake member 24 out of engagement with its cooperating friction surface and rendering the same inoperative. The brake member, however, will remain in engagement with the worm and will be connected therewith by the clutch teeth 29 so that the worm cannot rotate with relation to the shaft. Consequently the load can be lowered only as fast as the handle 35 is rotated. If the load is not sufficient to rotate the worm and move downward under its own weight then the action of the handle will rotate the worm 20 and cause the same to positively rotate the worm wheel and thus operate the screw in a reverse direction. When the load itself is sufficient to rotate the screw and worm wheel 19 then the worm 20 will be rotated by the worm wheel and will carry the shaft with it but if the 40 shaft is rotated at a greater speed than the handle the pin 33 will travel forwardly in the slot 32, thus permitting the end thrust on the worm to again seat the brake member and check the movement of the load. As a result any tendency of the load to run ahead of the handle will be immediately checked until the handle catches up with the shaft and the shaft is again moved axially to release the brake mechanism. 50 While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a lifting jack, the combination with a lifting element, and means for actuating the same to elevate a load, of a worm wheel connected with said lifting element for rotation thereby upon the downward movement of the load, a worm meshing with said worm wheel and capable of axial movement, a brake member actuated by the axial movement of said worm to prevent the rotation thereof, and means common to said brake member and said worm for moving said brake member into an inoperative position and for rotating said worm in a direction to lower the load on said lifting element. 75

2. In a lifting jack, the combination with a lifting element, and means for actuating the same to elevate the load, of a worm wheel connected with said lifting element for rotation thereby upon the downward movement of the load, a worm meshing with said worm wheel and capable of axial movement, a brake member actuated by the axial movement of said worm to prevent the rotation thereof, a lowering crank for rotating said worm in a direction to lower the load, and means controlled by the rotation of said crank to render said brake member inoperative, whereby said worm may be rotated and the load lowered. 90

3. In a lifting jack, the combination with a lifting element, and means for actuating the same to elevate a load, of a worm wheel connected with said lifting element for rotation thereby upon the downward movement of the load, a shaft, a brake connected with said shaft, a worm mounted on said shaft, meshing with said worm wheel and so arranged that the end thrust imparted thereto by said worm wheel will render said brake operative, a handle for rotating said shaft and said worm in a direction to lower the load and capable of a limited rotary movement with relation to said shaft, and means controlled by the movement of said handle with relation to said shaft to render said brake inoperative. 105

4. In a lifting jack, the combination with a lifting element, and means for actuating the same to elevate a load, of a worm wheel connected with said lifting element for rotation thereby upon the downward movement of the load, a shaft, a brake connected with said shaft, a worm mounted on said shaft, meshing with said worm wheel and so arranged that the end thrust imparted thereto by said worm wheel will render said brake operative, a handle rotatable about the axis of said shaft, and means controlled by said handle to render said brake inoperative and to rotate said worm. 110

5. In a lifting jack, the combination with a lifting element, and means for actuating 125

the same to elevate a load, of a worm wheel connected with said lifting element for rotation thereby upon the downward movement of the load, a shaft, a worm mounted on said shaft and meshing with said worm wheel, a brake member mounted on said shaft and arranged to be moved into an operative position by the end thrust imparted to said worm by said worm wheel, and means supported by said shaft for moving the same longitudinally to render said brake member inoperative.

6. In a lifting jack, the combination with a lifting element, and means for actuating the same to elevate a load, of a worm wheel connected with said lifting element for rotation thereby upon the downward movement of the load, a shaft, a worm mounted on said shaft and meshing with said worm wheel, a brake member mounted on said shaft and arranged to be moved into an operative position by the end thrust imparted to said worm by said worm wheel, an operating handle mounted on said shaft, means connected with said handle to impart axial movement to said shaft upon the initial movement of said handle and to then rotate said shaft.

7. In a lifting jack, the combination with a lifting element, and means for actuating the same to elevate a load, of a worm wheel connected with said lifting element for rotation thereby upon the downward movement of the load, a shaft, worm mounted on said shaft and meshing with said worm wheel, a brake member mounted on said shaft and arranged to be moved into an operative position by the end thrust imparted to said worm by said worm wheel, a sleeve mounted on said shaft and having a helical slot, a pin carried by said shaft and extending into said slot, and a handle connected with said sleeve.

8. In a lifting jack, the combination with a lifting element, and means for actuating the same to elevate a load, of a worm wheel connected with said lifting element for rotation thereby upon the downward movement of the load, a shaft, a worm mounted on said shaft and meshing with said worm wheel, a brake member mounted on said shaft and arranged to be moved into an operative position by the end thrust imparted to said worm by said worm wheel, a sleeve mounted on said shaft and having a helical slot, a pin carried by said shaft and extending through said slot, and a handle connected with said sleeve, said handle being pivotally mounted on said sleeve and having means to cause said pin and said sleeve to have relative movement when said handle is moved about the axis of its pivotal connection with said sleeve.

9. In a lifting jack, the combination with a lifting element, and means for actuating the same to elevate a load, of a worm wheel connected with said lifting element for rota-

tion thereby upon the downward movement of the load, a shaft mounted for both rotatory and axial movement, a brake member rigidly secured to said shaft, a worm mounted on said shaft for both rotatory and axial movement with relation thereto and meshing with said worm wheel, means controlled by the axial movement of said worm to connect it with said shaft when said worm is moved in one direction and to disconnect the worm from the shaft when the worm is moved in the other direction, and means for imparting axial movement to said shaft to render said brake member inoperative.

10. In a lifting jack, the combination with a lifting element, and means for actuating the same to elevate a load, of a worm wheel connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, and means for imparting axial movement to said shaft.

11. In a lifting jack, the combination with a lifting element, and means for actuating the same to elevate a load, of a worm wheel connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, a member rotatably mounted on said shaft, said member and said shaft having parts cooperating to impart axial movement to said shaft when said member is rotated in one direction, and means for actuating said member.

12. In a lifting jack, the combination with a lifting element, and means for actuating the same to elevate a load, of a worm wheel connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, a sleeve rotatably mounted on said shaft, held against axial movement in one direction and having a helical slot, a pin mounted on said shaft and extending into said slot, and a handle connected with said sleeve.

13. In a lifting jack, the combination with a lifting element, and means for actuating the same to elevate a load, of a worm wheel

connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, a sleeve rotatably mounted on said shaft, held against axial movement in one direction and having a helical slot, a pin mounted on said shaft and extending into said slot, a handle pivotally mounted on said sleeve on an axis transverse to the axis of said shaft, and means for retaining said handle in either of two positions with relation to said sleeve.

14. In a lifting jack, the combination with a lifting element, and means for actuating the same to elevate a load, of a worm wheel connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, a sleeve rotatably mounted on said shaft, held against axial movement in one direction and having a helical slot, a pin mounted on said shaft and extending through said slot, a handle pivotally mounted on said sleeve on an axis transverse to the axis of said sleeve, said handle having a part provided with locking recesses, and a plunger yieldably mounted on said sleeve for movement into and out of either of said recesses.

15. In a lifting jack, the combination with a lifting element, and means for actuating the same to elevate a load, of a worm wheel connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, a sleeve rotatably mounted on said shaft, held against axial movement in one direction and having a helical slot, a pin mounted on said shaft and extending through said slot, a handle pivotally mounted on said sleeve on an axis transverse to the axis of said sleeve, said handle having a hub portion provided with separated recesses, a plunger slidably mounted on said sleeve adjacent to said hub and having an enlarged portion adapted to enter one of the recesses in said hub, a spring tending to move said en-

larged portion of said plunger into said recess, said plunger having means for moving the same against the action of said spring to release said hub.

16. In a lifting jack, the combination with a lifting element, and means for actuating the same to elevate a load, of a worm wheel connected with said lifting element for rotation thereby upon the downward movement of the load, a shaft mounted for both rotatory and axial movement, a brake member rigidly secured to said shaft, a worm slidably and rotatably mounted on said shaft and meshing with said worm wheel, the adjacent ends of said worm and said brake member having cooperating clutch faces, a sleeve rotatably mounted on said shaft, held against axial movement in one direction and having a helical slot, a pin mounted on said shaft and extending through said slot, and a handle pivotally mounted on said sleeve on an axis transverse to the axis of said sleeve and having a cam-shaped portion arranged to engage said pin when said handle is moved in one direction about its axis.

17. In a lifting jack, a lifting element, an operating shaft connected with said lifting element for rotation in either direction thereby, a worm wheel rigidly secured to said shaft, a worm meshing with said worm wheel and capable of a limited axial movement, a brake member adapted to be connected with or disconnected from said worm, means controlled by the end thrust imparted to said worm by said worm wheel to connect said worm with said brake member and to render said brake member operative, and means for imparting axial movement to both said worm and said brake member to render said brake member inoperative.

18. In a lifting jack, a base, a standard rising from said base, a ram slidably mounted in said standard, a nut carried by said ram, a screw rotatably mounted on said base and operatively engaging said nut, a beveled gear rigidly connected with said screw, a beveled pinion meshing with said beveled gear, a gear rigidly connected with said pinion, a pinion meshing with the last mentioned gear, means for actuating said pinion, a worm wheel rigidly connected with said pinion, a worm meshing with said worm wheel, a brake member, means controlled by the end thrust imparted to said worm by said worm wheel to connect the same with and disconnect the same from said brake member and to render said brake member operative, and means for imparting axial movement to said worm and said brake member to render the brake member inoperative but retaining a connection between the same and the worm.

19. In a lifting jack, a base, a standard rising from said base, a ram slidably

6 mounted in said standard, a nut carried by said ram, a screw rotatably mounted on said base and operatively engaging said nut, a beveled gear rigidly connected with said

5 screw, a beveled pinion meshing with said beveled gear, a gear rigidly connected with said pinion, a pinion meshing with the last mentioned gear, means for actuating said pinion, a worm wheel rigidly connected with 10 said pinion, a shaft extending transversely to the axis of said worm wheel and mounted for rotatory and axial movement, a brake member rigidly connected with said shaft, a worm rotatably and slidably mounted on 15 said shaft and meshing with said worm wheel, said worm and said brake member having cooperating clutch faces, and an operating member connected with said shaft for imparting axial movement thereto to 20 render said brake member inoperative and for rotating the same to actuate said worm.

20. In a lifting jack, the combination with a lifting element, and means for actuating the same to elevate a load, of a worm wheel 25 connected with said lifting element for rotation thereby upon the downward movement of the load, a worm meshing with said worm wheel and capable of axial movement, a brake member actuated by the axial movement of said worm to prevent the rotation thereof, means for moving said brake member into an inoperative position and for rotating said worm in a direction to lower the 30 load on said lifting element, and means for positively locking said worm against rotation in a lowering direction.

21. In a lifting jack, the combination with a lifting element, and means for actuating the same to elevate the load, of a worm wheel connected with said lifting element 40 for rotation thereby upon the downward movement of the load, a worm meshing with said worm wheel and capable of axial movement, a brake member actuated by the axial movement of said worm to prevent the rotation thereof, a lowering crank, means controlled by the rotation of said crank to render said brake member inoperative, whereby said worm may be rotated and the 45 load lowered, and means controlled by said crank to positively lock said worm against rotation in a lowering direction.

22. In a lifting jack, the combination with a lifting element, and means for actuating the same to elevate a load, of a worm wheel connected with said lifting element 55 for rotation thereby upon the downward movement of the load, a shaft, a brake connected with said shaft, a worm mounted on 60 said shaft, meshing with said worm wheel and so arranged that the end thrust imparted thereto by said worm wheel will render said brake operative, a handle connected with said shaft and capable of a limited rotation 65 about the axis thereof, means controlled by

said handle to render said brake inoperative, said handle being movable about an axis transverse to said shaft into an inoperative position, and means cooperating with said handle when the latter is in an inoperative position to hold said shaft positively against rotation in a lowering direction. 70

23. In a lifting jack, the combination with a lifting element, and means for actuating the same to elevate a load, of a worm wheel 75 connected with said lifting element for rotation thereby upon the downward movement of the load, a shaft mounted for both rotatory and axial movement, a brake member rigidly secured to said shaft, a worm 80 slidably and rotatably mounted on said shaft and meshing with said worm wheel, the adjacent ends of said worm and said brake member having cooperating clutch faces, a sleeve rotatably mounted on said shaft, held against axial movement in one direction and having a helical slot, a pin mounted on said shaft and extending into said slot, a handle pivotally mounted on said sleeve on an axis 85 transverse to the axis of said shaft, means for retaining said handle in either of two positions with relation to said sleeve, and a fixed stop to engage said handle when the latter is in one of said positions to hold said handle and sleeve against movement in a 90 lowering direction. 95

24. In a lifting jack, the combination with a lifting element, and means for actuating the same to elevate a load, of a device to control the downward movement of said lifting element comprising a brake, a movable member to render said brake operative, means for connecting said movable member with said lifting element to cause the former to be moved in a direction to set the brake 100 by the downward movement of said lifting element, and manually operated means for moving said movable member against the action of said lifting element to relieve the pressure on said brake and for actuating said 105 movable member to permit of the downward movement of said lifting element. 110

25. In a lifting jack, the combination with a lifting element, and means for actuating the same to elevate a load, of a device to control the downward movement of said lifting element comprising a brake, a movable member to render said brake operative, means for connecting said movable member with said lifting element to cause the former to be moved in a direction to set the brake by the downward movement of said lifting element, and a single device for moving said movable member against the action of said lifting element to release the pressure on said brake 115 and for actuating said movable member to permit of the downward movement of said lifting element. 120

26. In a lifting jack the combination with a lifting element, and means for actuating 125

the same to elevate a load, of a device to control the downward movement of said lifting element comprising a brake, a movable member to render said brake operative, means for connecting said movable member with said lifting element to cause the former to be moved in a direction to set the brake by the downward movement of said lifting ele-

ment, and a handle connected with said movable member for moving the same against 10 the action of said lifting element to relieve the pressure on said brake.

In testimony whereof, I affix my signature hereto.

ION V. K. HOTT.
